HENRY SPEARMAN.

BY *James Griffith*,
ATTORNEY

UNITED STATES PATENT OFFICE.

HENRY SPEARMAN, OF SAN MATEO, CALIFORNIA.

SECTIONAL MAGAZINE RACK.

Application filed December 16, 1927. Serial No. 240,445.

The present invention relates to improvements in display racks for literature, and more particularly to racks for the display of magazines, books and productions of such like character.

- A primary object of my invention is the provision of a rack for the retention of magazines and the like that is of simple and inexpensive construction, that is provided 10 with adjustable retaining means adapted for adjustment to accommodate various sized magazines, and that is of a character suitable for mounting upon a wall or other upright support.
- 15 A further object of the invention is the provision of a readily assembled device of the character indicated that is particularly adaptable to the utilization of vacant wall spaces.
- 20 Additional to the foregoing is that of embodying in a rack construction of the character indicated novel adjustable retaining members adapted for the retention in place of the upper ends of such articles as are 25 carried by the supporting channels of the rack.

Another object of my invention is the provision of a rack of the character designated that may be constructed in sections of varying 30 widths provided with interlocking hook members so arranged that additional sections may be added from time to time as additional rack capacity may be required, these sections being of a nature permitting their 35 nesting together as a convenience when being prepared for shipment.

Other objects and advantages of the invention will become apparent as this specification progresses and be more fully 40 brought out in the claims hereto appended.

In the accompanying drawings, forming a part of this specification, and, in which, similar characters of reference designate like parts, throughout:

45 Figure 1 is a front elevation, showing an article rack constructed in accordance with the principles of my invention, with the article retaining members in normal retaining positions relative thereto;

50 Figure 2 is an edge view of the device, in which the rack is shown as being suspended from a hook secured in any desired manner to an upright structure, such as a wall of a room or other building;

55 Figure 3 is a top plan view, further illustrative of the retaining members;

Figure 4 is an enlarged sectional detail, taken through a portion of the rack and showing the method of slidably supporting the retaining members relative thereto, the 50 section being indicated by the line 4—4 of Figure 1;

Figure 5 is a sectional detail, taken through one of the rack sections and its retaining member, the section being indicated 65 by the line 5—5 of Figure 1;

Figure 6 is a sectional detail illustrative of a sectional form of rack;

Figure 7 is a sectional detail illustrative of a slightly modified form of retaining 70 member, rods being here used instead of flat sheet metal;

Figure 8 is an enlarged fragmentary edge view, illustrative of a sectional form of rack in which the various sections are provided 75 with interlocking hooks adapted to engage the lower supporting channel edges, as shown; and

Figure 9 is an end view of a portable rack, mounted upon casters, embodying the principles of my invention.

Referring more particularly to the drawings, the numeral 10 designates the rack as a whole, the rack being either constructed in sections or formed from a single piece of 85 sheet metal, as shown in Figures 1 and 2, the latter being the preferred form. The rack is formed in a sheet metal "break" and consists of a right angled bend 11 terminating in upwardly bent ears 12, these ears being 90 provided with perforations 13 adapted to receive hooks 14 or other means for the retention and support of the rack upon a wall or other support 16, as indicated in Figure 2.

The rack shown in Figures 1, 2, 3 and 4 consists of three article holding panels 17, 18 and 19 having channels 20, 21 and 22 formed transversely thereof at their lower ends and in which a plurality of books or 100 magazines 23 are intended to be supported. Each of the panels 17, 18 and 19 extend angularly and downwardly, as shown in Figure 2, with their inner edges resting against the upright support 16 as shown.

A plurality of retaining members 24 are positioned horizontally upon the panels 17, 18 and 19, embracing the rack and arranged to retain the upper ends of the articles 23, the retaining members each consisting of 110 sections of sheet metal bent upon themselves and flattened down, as shown in section in

Figure 5, comprising substantially L-shaped members 26 and 27 having frontal sections 28 and 29 fitting into sleeves 30, the inner end of the section 29 being soldered in the 5 end of said sleeve 30 at the point 31 and the inner end of the section 28 free to slide back and forth in said sleeve, thus providing means for lateral adjustment of both said members 26 and 27 relative to each other 10 and to the various panels of the rack 10, for the accommodation of the varying widths of books and magazines, as clearly shown in Figure 1.

The members 26 and 27 terminate in the 15 rear of the rack in rearwardly projecting lugs 32 and 33, these lugs acting as stops to prevent the members 26 and 27 from being entirely separated, the while the rear sections 34 and 35 of the members 26 and 27 are 20 slidably mounted in rearwardly projecting guide loops 36 and 37 formed in the panels by slitting the metal and punching it rearwardly, as shown in Figures 4, 5 and 7.

Intermediately positioned supports 38 are 25 mounted in the panels and project outwardly therefrom and consist of ordinary L-shaped hooks having their inner ends soldered or otherwise secured in holes formed in the panels for their reception, these hooks affording support for the sleeves 30 and the members 28 and 29 for the prevention of the sagging of these features.

In Figure 7, I have shown a modified form, in which the members 39 are of steel 35 rod formation, replacing those of flat metal construction, with supports 40 provided with eyelets 41 as replacements for the hooks 38, for the accommodation of the tubular sleeve 30.

In Figures 6 and 8, I have illustrated a 40 rack constituted of several panels 42 of sectional form, comprising a plurality of interlocking sections 43, as shown, the retaining members being identical, both in construction 45 and arrangement, with those shown in Figures 1 to 5 inclusive.

In Figure 9, I have shown a portable arrangement on casters 47, similar in every 50 particular to the racks illustrated in Figures 1 to 5 inclusive, except in that two racks 45 and 46 are employed with the racks arranged back to back, the casters permitting transference from place to place without derangement of effects. The retaining members 48 are here the exact counterpart of those previously described, with four panels 49 shown instead of three, and these suitably braced by a series of shelves 50 adapted to be utilized also for display purposes.

In placing books or magazines upon the 60 rack for display, they are first placed within the loops forming the retaining members, and thereafter dropped into place, with their lower edges resting within the supporting channels and their upper resting

against the retaining members, as shown in Figures 2 and 8.

Articles thus displayed may be readily selected from the rack by either the purchaser or the dealer. As a display device it 70 presents a much neater appearance, creates a more favorable impression and adds greatly to facilities for the handling of literary productions and is particularly well adapted to the needs and conveniences of the 75 smaller stores where display space is usually quite inadequate.

Having thus described my invention, I claim, and desire to secure by Letters Patent:

1. A device of the class described, comprising a sheet metal rack section embodying a plurality of superposed panels, each provided with article supporting channels, supporting ears formed on the upper of said panels and providing means for suspending the rack from an upright support, retaining members consisting of a pair of elements slidably mounted upon said panels and adapted to retain the upper ends of the supported articles, said retaining members bearing sleeves adapted to allow of lateral movement of the elements thereof relative to each other to increase their capacity, and means coacting therewith to limit their lateral movement and to prevent their complete 95 separation.

2. In a device of the class described, a sheet metal rack section embodying a plurality of panels provided at their lower edges with article supporting channels, 100 aligned guide loops formed in each of said panels, retaining members having their rear sections slidably retained by said loops and their frontal sections terminating in aligned relation, sleeves mounted upon said aligned sections and providing means for their lateral adjustment relative to each other to increase their holding capacity, and lugs carried by the inner ends of the rear sections of said retaining members and adapted to 105 engage said loops to prevent the complete separation of said members.

3. In a device of the class described, comprising a sheet metal rack section embodying a plurality of superposed panels, aligned 115 guide loops formed in each of said panels, adjustable retaining members of L-shaped configuration having their rear sections slidably mounted in said loops and their frontal sections terminating in aligned relation, sleeves mounted upon said aligned sections, and supporting hooks carried by said panels and embracing said sleeves to provide intermediate supports for said retaining members.

4. In a device of the class described, a sheet metal rack section embodying a plurality of superposed panels, aligned guide loops formed in each of said panels, laterally 120 adjustable retaining members of L-shaped 125 configuration having their rear sections slidably mounted in said loops and their frontal sections terminating in aligned relation, sleeves mounted upon said aligned sections, and supporting hooks carried by said panels and embracing said sleeves to provide intermediate supports for said retaining members.

configuration having their rear sections slidably mounted in said loops and their frontal sections terminating in aligned relation, sleeves mounted upon said aligned sections and telescoping the same, supporting hooks projecting from said panels and embracing said sleeves to provide intermediate supports for said retaining members, and lugs carried by the rear sections of said re-

taining members and adapted to engage the inner of said guide loops to limit the lateral adjustment of said retaining member sections.

In testimony whereof, I have hereunto affixed my signature this fifth day of December A. D., 1927.

HENRY SPEARMAN.
